APPARATUS FOR MAKING FIBROUS MATERIALS

Ernest Hopkinson, New York, N. Y., assignor to
The Naugatuck Chemical Company, Naugatuck, Conn., a corporation of Connecticut

Application April 5, 1930, Serial No. 441,833

6 Claims. (Cl. 92—60)

The present invention relates to a method and apparatus for obtaining combinations of fibrous material in which the fibres are intermingled in all directions and without stratification. More particularly it relates to the production of combinations of fibrous materials wherein the fibres are bound together by a binder material such as rubber, which may be applied in the form of latex or other water dispersions of rubber.

10 My process briefly comprises confining a wet mass of fibrous material which may contain a binder material and any other desired ingredients, compacting the mass by exerting pressure on it in a plurality of directions, and expressing the excess fluid from the mass. If sheet material is made on an ordinary paper making machine, or if a wet pulp mass is allowed to drain on a foraminous material or is compacted by exerting pressure in one direction as by exerting pressure on a mass against a fixed backing or compressing between parallel platens, a stratification of the finished product will result due to the parallel disposition of the fibres in the compressed mass. By exerting pressure on the 15 wet mass in a plurality of directions, as above described, I prevent any substantial stratification of the fibres and I produce a compressed mass with the fibres intermingled in all directions and without stratification.

20 25 30

In the drawings I have shown an apparatus capable of producing the desired results, but it will be understood that such is exemplary of only one apparatus in which the invention may be carried out and that the specific form of apparatus may differ widely from that illustrated.

In the drawings, Figure 1 is a cross-sectional view of the apparatus in charging position.

Figure 2 is a similar view showing the relationship of the parts on the completion of the water expressing operation; and

Figure 3 is a longitudinal section.

Referring to the drawings in detail, 1 is a bed plate; 2 represents the side plates and 3 designates the top cover. The bottom plate 1 may be supported in any desired manner and the top plate 3 may be raised and lowered by any desired means. The top plate 3 and the two side plates 2 are each provided with a sheet of flexible material, preferably rubber, 4, secured only at its edge portions in a suitable manner as by clamping strips 10 secured in corresponding grooves of the top and side plates by screws 11. Each of the side plates 2 and the top plate 3

are provided with fluid inlet ports 6, for the purpose hereinafter described.

The two side plates 2 and the bottom plate 1 form a box-like structure whose ends are closed by the end plates 5.

On the bed plate 1 is located a sheet of porous filtering material 7 and a fine meshed wire sheet 8, which serves as supporting and filtering medium for the batch of wet pulp which is being acted on.

The method of operation is as follows: The parts being in the position shown in Figure 1, the box-like cavity is filled with the desired composition of matter comprising fibrous material, latex and/or water dispersions of rubber, and any other desired ingredients depending upon the character of the product desired to be obtained. The fibrous material may be asbestos fibre or cellulose or similar fibre. It may be prepared in any desired manner. In the case of cellulose fibre, it may have been subjected to a preliminary beating operation and the latex or rubber dispersion may be in any desired form such as a highly fluid condition with a comparatively low rubber content, or concentrated latex, or ordinary latex or rubber dispersion which has been subjected to a thickening or gelling process. The top plate 3 is then lowered to close the top of the box-like cavity, a tight joint being made by the rubber surfaces 4 on the side plates and cover coming in contact with each other to act as a packing material.

In the drawings, it is designed that the top plate should be raised and lowered by an appropriate piston and cylinder arrangement—not shown in detail. After the parts are in the position shown in Fig. 2, fluid pressure is admitted through the inlet ports 6, causing the rubber sheets 4 to stretch away from their respective backing plates 2, 2, and 3, so that pressure is exerted on three sides of the contained mass of material which results in expressing the fluid from the material through the wire mesh 8 and filtering sheet 7 through the drainage ports 9.

This operation is preferably continued until the major portion of the fluid content of the mass is expressed, leaving a cohering mass of fibers in which the individual fibers are intermingled in substantially all directions without stratification and, the intermingled cohering fibers having a low water content—approximately 20%—is non-flowing and capable of sustaining its compressed shape.

The fluid back of the rubber sheets 4 is then withdrawn to permit the rubber sheets to come back to first position, leaving the compressed mass of fibrous material occupying the central portion of the box-like structure. The top plate is then raised and one of the end plates removed and the compressed mass of fibrous material removed for further drying operations.

One important use of the product thus produced is in the preparation of shoe sole material approximating the fibrous structure of leather. To obtain this result the removed mass may be subjected to further drying as above described and then cut into sheets either in a longitudinal or cross-sectional direction and the individual sheets subjected to a relatively high pressure, preferably under the action of heat.

Many widely different variations of apparatus may be designed to carry out the desired results. Those illustrated are merely indicative of a simple apparatus by which the method can be carried into effect.

Having thus described my invention, what I claim and desire to protect by Letters Patent is:

1. An apparatus for compacting a mass of fibrous material comprising a closed receptacle having a plurality of walls, at least one wall having passages from the interior of the receptacle to the outside thereof, at least two non-parallel walls having pressure exerting elements capable of simultaneous movement away from said walls toward the interior of the receptacle to exert uniform pressure over the entire contacting surfaces of the mass.

2. An apparatus for compacting a mass of fibrous material comprising a closed receptacle having a plurality of walls, at least one wall hav-

ing passages from the interior of the receptacle to the outside thereof, at least two non-parallel walls having resilient pressure exerting elements capable of simultaneous movement away from said walls toward the interior of the receptacle to exert uniform pressure over the entire contacting surfaces of the mass.

80

3. An apparatus for compacting a mass of fibrous material comprising a closed receptacle having a plurality of walls, and at least two non-parallel walls having pressure exerting elements capable of simultaneous movement away from said walls toward the interior of the receptacle.

86

4. An apparatus for compacting a mass of fibrous material comprising a closed receptacle having a plurality of walls, and at least two non-parallel walls having resilient pressure exerting elements capable of simultaneous movement away from said walls toward the interior of the receptacle.

90

5. An apparatus for compacting a mass of fibrous material comprising a closed receptacle having a plurality of walls, and at least two non-parallel walls having elastic members attached thereto, and means for expanding said elastic members away from said walls toward the interior of the receptacle.

95

6. An apparatus for compacting a mass of fibrous material comprising a closed receptacle having a plurality of walls, at least one wall having passages from the interior of the receptacle to the outside thereof and at least two non-parallel walls having elastic members attached thereto, and means for expanding said elastic members away from said walls into the interior of the receptacle.
